(57) **CLAIM**

The ornamental design for a dish as shown and described.

DESCRIPTION

1. Dish
2. Dish
- 1.1 : Perspective
- 1.2 : Perspective
- 1.3 : Top
- 1.4 : Left
- 2.1 : Perspective
- 2.2 : Perspective
- 2.3 : Top
- 2.4 : Left

The dish is round. Rising from a circular base, the sides widen abruptly and the rim opens and widens. Parallel reliefs surround the underside of the curved part of the rim. The rim of the dish forms a handle by widening abruptly.
